(57) **CLAIM**

The ornamental design for a tire, as shown and described.

DESCRIPTION

1.Tire

FIG. 1.1 is a front view of a tire showing my new design; FIG. 1.2 is an enlarged partial view thereof; FIG. 1.3 is a left perspective view thereof; FIG. 1.4 is an enlarged partial view of FIG. 1.3; FIG. 1.5 is a left view of FIG. 1.1; FIG. 1.6 is a right perspective view thereof; FIG. 1.7 is an enlarged partial view of FIG. 1.6; and FIG. 1.8 is right view of FIG. 1.1.

The dashed-dot broken lines in FIG. 1.1, FIG. 1.3 and FIG. 1.6 are demarcations of the portion of the design visible in the enlarged partial views of FIG. 1.2, FIG. 1.4 and FIG. 1.7, and form no part of the claimed design.
